INITIAL WRIST WATCH CASE

Benjamin Lazarus, Lawrence, Long Island, N. Y.,
assignor to Benrus Watch Company, New York,
N. Y., a corporation of New York

Application May 18, 1939, Serial No. 274,369

13 Claims. (Cl. 58—88)

This invention relates to watch cases and more particularly to wrist watch cases arranged to receive initials.

Vest pocket watches have been engraved on the back or reverse side, though some people objected to such engraving as making it impossible to transfer or dispose of the watch in the event of need. Wrist watches, for the most part, have not been engraved because the back is not exposed. The present invention concerns watch cases provided with means on the front face outside the crystal for receiving cut-out initials, numerals or other indicia. Such a watch is personalized with bold metal characters of seeming permanence, yet which in fact may be added from a supply of characters by the watch dealer at the time the watch is sold, or resold.

One object of my invention is to provide a wrist watch case with a comparatively smooth or continuous bezel, said bezel having a main opening for the watch crystal, and one or more auxiliary openings for initials which are inserted from beneath the bezel. By this construction the watch is given a well finished and attractive appearance.

The initials are cut or stamped out of metal and are exposed through the initial opening. A further object of the present invention is to prevent the possibility of dust passing through the spaces between the initials into the watch movement, that is, to keep the watch case dustproof. To this end, I provide sealing plates which are applied beneath the initials and are detachably secured in place, said sealing plates functioning to hold the initials in the initial opening, and to seal up the opening against the admission of dust.

In accordance with further features and objects of the present invention, the initials are cut out of metal of substantial thickness, thus providing the initials with considerable depth, so that they project through the initial opening and are exposed above the top face of the bezel. Moreover, the depth is made several times the thickness of the initials, thus giving the same an attractive, moderne and expensive appearance. The initials may be cut from a metal of contrasting color as, for example, by using silver or white gold initials in a yellow gold case. With this combination the sealing plate is also preferably made of yellow gold. The initials may be provided with shallow locating portions at their bottom, these portions being received beneath the bezel outside the initial opening to limit upward movement of the initials. The locating

portions preferably project sidewardly to space the initials apart, and to prevent sideward movement of the initials in the bezel.

To the accomplishment of the foregoing and other objects which will hereinafter appear, my invention consists in the watch case and initial elements and their relation one to the other, as hereinafter are more particularly described in the specification and defined in the claims. The specification is accompanied by a drawing, in which:

Fig. 1 is a plan view of a wrist watch case embodying features of the present invention;

Fig. 2 is a side elevation of the same;

Fig. 3 is a perspective view of one of the letters used with the wrist watch case;

Fig. 4 is a partially sectioned view in perspective of a fragment of the wrist watch case;

Fig. 5 is a bottom view of the bezel with one of the sealing plates and an initial removed;

Fig. 6 is a fragmentary section taken in the plane of the line 6—6 of Fig. 1, and drawn to enlarged scale; and

Fig. 7 is a transverse section taken in the plane of the line 7—7 of Fig. 1.

Referring to the drawing, the wrist watch case comprises an upper portion or bezel generally designated 12 and a lower portion generally designated 18. The lower portion is suitably shaped and dimensioned to receive a wrist watch movement in conventional fashion, the particular case here shown being provided with a dropped portion or well 16, as is more fully described in my Patent 2,069,453 granted February 2, 1937. The bottom half may itself be made of two parts, the lower part being upwardly flanged at 17 (Fig. 7) to receive a frame-like upper part 18, best shown in Figs. 6 and 7, the latter being brazed into the bottom to form a permanent union therewith. The frame-like part 18 accurately receives and locates the movement. The bezel 12 fits telescopically over the part 18 until it meets the upwardly flanged edge 17 of the lower portion in flush relation thereto. The parts may be locked together with a snap engagement, as is indicated at 20 in Fig. 6.

The bezel portion 12 is provided with a main opening 22 which receives a crystal 24. The metal at the inside of opening 22 is turned or flanged inwardly, as is indicated at 26 and 28, these flanges being so shaped as to form a seat for the edges of the crystal 24. The periphery of the bezel is flanged downwardly, thus providing the side walls 30 and end walls 32.

Outside the crystal opening the bezel is pro-

vided with an initial opening 34. This opening is preferably elongated and is most simply made rectangular. For the sake of symmetry, I prefer to provide two such openings, as is shown in the drawing. The openings are located between the flanges 26 and 32, and the surface metal of the bezel surrounding the openings 34 constitutes a frame which outlines the initials which are subsequently added. The bezel, as thus far described, is preferably made of a single piece of metal which is appropriately stamped and shaped in dies.

The bezel is provided at its ends with appropriate means for attaching a wrist strap. In the present case this comprises ears 38 which are brazed to the ends of the bezel and which are apertured, as indicated at 40 (Fig. 6) to detachably receive the bails connecting the ends of the wrist strap. It will be understood that the wrist strap may be of any desired type, such as those made of leather, chain, cord and the like.

The jeweler selling this type of watch is provided with a supply of letters, numerals, or other indicia, such as may be wanted by the trade in that particular locality. For example, for graduation purposes initials may be used at one end and class numerals at the other. For fraternal purposes initials may be used at one end and Greek fraternity letters at the other, and so on. The construction of the individual letters will be clear from inspection of Fig. 3, the letters being cut or stamped out of comparatively thick metal, as is indicated at 42, and having flanges or locating means 44 preferably formed integrally with the initials. These parts extend above and below the initials in order to limit upward movement of the initials through the opening. The initials are dimensioned to just fit between the frame parts 46 of the bezel, as is best shown in Figs. 4 and 6 of the drawing, while the parts 44 of the initials underlie the frame parts 46 and prevent upward movement of the initials through the opening. The parts 44 are preferably extended sidewardly, as is clearly shown in Fig. 3 in order to act as spacing means to hold the letters apart. This is clearly shown in Fig. 5, in which it will be seen that the parts 44 of the successive initials come into abutting relation and are so dimensioned that, in the present case, three initials exactly fill the length of the initial opening. When only two initials are to be used, appropriate spacers are provided to be used at the ends in order to properly center the two initials.

The initials are held in place by sealing plates 50. These are detachably held in position by suitable means here illustrated as tiny watch screws 52 (Figs. 5 and 6). These screws are received in threaded openings formed in small blocks 54, said blocks being brazed to the inside of the bezel at the ends of the initial openings. The sealing plates 50 are preferably stepped downwardly slightly to accommodate the blocks 54, the latter being used, of course, in order to provide adequate depth of thread for the screws 52 without marring the outer or top surface of the bezel.

The sealing plates 50 function to hold the initials snugly against the frame parts 46 of the bezel. They serve an additional function in sealing the case against the admission of dust to the watch movement. For this purpose the side edges of the sealing plates are flanged upwardly, as is best shown in Figs. 4 and 6, and the sealing plate is dimensioned to fit very snugly and accurately between the downwardly turned flanges

26 and 32 of the bezel. The fit of the parts is preferably made such that the watch may be shipped and displayed without initials, the initial openings being fully sealed by the sealing plates. When the watch is sold and the desired initials are specified, the dealer simply opens the watch case, removes the sealing plates, applies the initials, replaces the sealing plates, and again closes the case.

The depth of the initials is preferably made substantial and it is appreciably greater than the thickness of the bezel at the frame parts 46. In this way the initials are allowed to project upwardly through the frame, as is clearly shown in the drawing. Moreover, the depth of the initials is preferably greater than the thickness of the same, thus giving the initials a costly, attractive, modern appearance. The initials may, of course, be made of contrasting color as, for example, by using silver or white gold initials with a yellow gold bezel.

It is believed that the construction and method of use, as well as the many advantages of my improved initial watch case, will be apparent from the foregoing detailed description thereof. It will be understood that a single initial opening may be provided, instead of two, as here illustrated. It will also be apparent that while I have shown and described my invention in a preferred form, many changes and modifications may be made in the structure disclosed without departing from the spirit of the invention defined in the following claims. In the claims the term "wrist strap" is intended to include a band or chain, etc. The term "initial" is intended to include numerals or other indicia, as well as letters.

I claim:

1. A watch case comprising a crystal holding section at its exposed top face, an opening through the top of the case outside the crystal holding section, separable and interchangeable initials inserted from beneath and exposed through said opening, and means detachably secured directly beneath said initials inside said case for holding the initials at said opening.

2. A wrist watch case comprising a crystal holding section at its exposed top face, means at the ends for attachment to a wrist strap, the case having openings on opposite sides of the crystal holding section between said section and said end attaching means, separable and interchangeable initials inserted from beneath and exposed through said openings, and sealing plates detachably secured directly beneath said initials in order to hold the initials and to seal the case against the admission of dust through the initial openings.

3. A wrist watch case comprising a crystal holding section at its exposed top face, means at the ends for attachment to a wrist strap, the case having openings on opposite sides of the crystal holding section between said section and said end attaching means, separable and interchangeable initials inserted from beneath and exposed through said openings, said initials being thick so that the tops of the initials project upwardly through the openings, said initials having locating means at the bottom which are disposed beneath the top of the watch case and outside the openings in order to prevent upward movement of the initials and to space the same apart, and sealing plates detachably secured beneath said initials in order to hold the initials and to seal the case against the admission of dust through the initial openings.

4. A wrist watch case comprising a bottom half so shaped and dimensioned as to receive a wrist watch movement, a bezel dimensioned to fit over said bottom half with a snap engagement, said bezel comprising a single piece of metal flanged at its sides and provided with a crystal opening and an initial opening outside of the crystal opening, means at the ends of said bezel for attachment of a wrist strap, the portion of the bezel immediately surrounding the initial opening acting as a frame for the initials, initials interchangeably disposable in said frame from beneath, the initials being exposed through the initial opening, a removable sealing plate beneath the initials to hold the same tightly and to seal the bezel against the admission of dust into the watch case, and means for detachably securing said sealing plate in position.

5. A wrist watch case comprising a bottom half so shaped and dimensioned as to receive a wrist watch movement, a bezel dimensioned to fit over said bottom half, said bezel comprising a single piece of metal flanged at its sides and provided with a crystal opening and elongated initial openings at each end of the crystal opening, means at the ends of said bezel for attachment of a wrist strap, the portion of the bezel immediately surrounding each initial opening acting as a frame for the initials, initials interchangeably disposable in said frame from beneath, said initials having locating portions disposed beneath the frame to prevent upward movement of the initials and projecting sidewardly to space the initials apart and to prevent sideward movement of the initials in the frame, a removable sealing plate beneath the initials to hold the same tightly and to seal the bezel against the admission of dust into the watch case, and means for detachably securing said plate tightly in position.

6. A wrist watch case comprising a bottom half so shaped and dimensioned as to receive a wrist watch movement, a bezel dimensioned to fit telescopically over said bottom half, said bezel comprising a single piece of metal flanged at its sides and provided with a crystal opening and rectangular initial openings at each end of the crystal opening, means secured at the ends of said bezel for attachment of a wrist strap, the portion of the bezel immediately surrounding each initial opening acting as a frame for the initials, initials interchangeably disposable in said frame, said initials being of substantial depth, the initials being dimensioned to fit through the frame opening and to project thereabove and having locating portions at the bottom of the initials which are disposed beneath the frame to limit upward movement of the initials and which project sidewardly to space the initials apart and to prevent sideward movement of the initials in the frame, a removable sealing plate beneath the initials to hold the same tightly and to seal the bezel against the admission of dust into the watch case, and screws at the ends of said sealing plates for securing same tightly in position.

7. A wrist watch case comprising a bottom half so shaped and dimensioned as to receive a wrist watch movement, a bezel dimensioned to fit over said bottom half, said bezel comprising a single piece of metal flanged at its edges and provided with a crystal opening, and rectangular initial openings at each end of the crystal opening, the bezel being flanged downwardly at the ends of the crystal opening, the portion of the bezel immediately surrounding each initial opening acting as a frame for the initials, with the aforesaid bezel flanges being located at the outer edges

10 of said frame, initials interchangeably disposable in said frame, said initials being of substantial depth and being dimensioned to fit through the frame openings, said initials having locating portions at the bottom which are disposed beneath the frame to limit upward movement of the initials, and a removable sealing plate beneath the initials and fitting closely between said flanges to hold the initials and to seal the bezel against the admission of dust.

8. A wrist watch case comprising a bottom half shaped and dimensioned to receive a watch movement, a top half fitting over the bottom half, means at the ends of the top half to receive a wrist strap, said top half having an opening for receiving a crystal, and having one or more additional openings outside the crystal for receiving initials, initials disposed in said one or more additional openings from beneath, said initials having letter portions exposed through the one or more additional openings, and further having locating portions received beneath the top half of the watch case outside the one or more additional openings, said locating portions projecting at each side in order to properly space the letters relative to one another, and a removable sealing plate disposed beneath the letters to hold the same in position and to seal the interior of the watch case against the admission of dust through the spaces between the initials.

9. A wrist watch case comprising a crystal holding section at its exposed top face, means at the ends for attachment to a wrist strap, the case having openings on opposite sides of the crystal holding section between said section and said end attaching means, separable and interchangeable initials inserted from beneath and exposed through said openings, said initials being thick so that the tops of the initials project upwardly through the openings, and means detachably secured beneath said initials in order to hold the initials in the initial openings.

10. A wrist watch case comprising a crystal holding section at its exposed top face, means at the ends for attachment to a wrist strap, the case having openings on opposite sides of the crystal holding section between said section and said end attaching means, separable and interchangeable initials inserted from beneath and exposed through said openings, said initials having locating means disposed beneath the top of the watch case and outside the openings in order to prevent upward movement of the initials, and means detachably secured beneath said initials in order to hold the initials in the initial openings.

11. A wrist watch case comprising a crystal holding section at its exposed top face, means at the ends for attachment to a wrist strap, the case having openings on opposite sides of the crystal holding section between said section and said end attaching means, separable and interchangeable initials inserted from beneath and exposed through said openings, said initials having locating means disposed beneath the top of the watch case to space the initials apart, and means detachably secured beneath said initials in order to hold the initials in the initial openings.

12. A watch case comprising a crystal holding section at its exposed top face, the case also having an initial opening outside the crystal holding section, separable and interchangeable initials inserted from beneath and exposed through said opening, said initials being thick so that the tops of the initials project upwardly through the opening, said initials having locating

means at the bottom which are disposed beneath the top of the watch case and outside the openings in order to prevent upward movement of the initials and to space the same apart, and means detachably secured beneath said initials in order to hold the initials in the initial openings.

13. A watch case including a bezel provided with a crystal opening and an initial opening outside the crystal opening, the portion of the bezel immediately surrounding the initial opening acting as a frame for the initials, said bezel having a flange on its lower side surrounding said frame, initials interchangeably disposable in said frame, said initials having locating portions disposed beneath the frame to limit upward movement of the initials, and a removable sealing plate disposed beneath the initials and fitting closely within the aforesaid frame flange to hold the initials and to seal the bezel against the admission of dust into the watch case.

14. A watch case including a bezel provided with a crystal opening and an elongated rectangular initial opening outside the crystal opening, the portion of the bezel immediately surrounding the initial opening acting as a frame for the initials, said bezel having a flange on its lower side surrounding said frame, initials interchangeably disposable in said frame, said initials being of substantial depth and dimensioned to fit through the frame openings and to project thereabove, and having locating portions at their bottom which are disposed beneath the frame to limit upward movement of the initials and which project sideward to space the initials apart and to prevent sideward movement of the initials in the frame, a removable sealing plate disposed beneath the initials and fitting closely within the aforesaid frame flange to hold the initials and to seal the bezel against the admission of dust

into the watch case, and screws for securing the sealing plate tightly in position.

15. A watch case having a crystal holding section at its exposed top face, an opening through 5 the top of the face outside the crystal holding section, separable and interchangeable initials inserted from beneath and exposed through said opening, and means to seal the case against the admission of dust to the watch movement through the initial openings.

16. A watch case having a crystal holding section at its exposed top face, an opening through 15 the top of the face outside the crystal holding section, separable and interchangeable initials inserted from beneath and exposed through said openings, and a sealing plate detachably secured directly beneath said initials in order to hold the initials and to seal the case against the admission of dust through the initial openings.

20 17. A wrist watch case comprising a crystal holding section at its exposed top face, means at the ends for attachment to a wrist strap, the case having openings on opposite sides of the crystal holding section between said section and said end attaching means, separable and interchangeable initials inserted from beneath and exposed through said openings, and means beneath said initials to hold the initials at the openings.

30 18. A wrist watch case comprising a crystal holding section at its exposed top face, means at the ends for attachment to a wrist strap, the case having openings on opposite sides of the crystal holding section between said section and said end attaching means, separable and interchangeable initials inserted from beneath and exposed through said openings, and means to seal the case against the admission of dust to the watch movement through the initial openings.

BENJAMIN LAZRUS.
